UNITED STATES PATENT OFFICE.

ALLIE DILLARD, OF OLD CHURCH, VIRGINIA.

DRILL-HOE.

SPECIFICATION forming part of Letters Patent No. 339,154, dated April 6, 1886.

Application filed December 22, 1885. Serial No. 186,488. (No model.)

To all whom it may concern:

Be it known that I, ALLIE DILLARD, a citizen of the United States, residing at Old Church, in the county of Hanover and State 5 of Virginia, have invented a new and useful Improvement in Drill-Hoes, of which the following is a specification, reference being had to the accompanying drawings.

My invention relates to an improvement in 10 drill-hoes; and it consists in the peculiar construction and combination of devices that will be more fully hereinafter set forth, and particularly pointed out in the claims.

In the drawings, Figure 1 is an elevation of 15 a drill-hoe with my improvement attached thereto. Fig. 2 is a vertical section of the same.

A represents a drill-hoe, which is of the ordinary construction, and to the lower end of 20 which is attached the usual shoe or shovel, B.

C represents a standard, which is provided at its upper end with a vertical slot, D, and at a suitable distance below the slot D with a circular opening, E, which is considerably 25 larger in diameter than the transverse diameter of the slot. From the lower end of the standard C, on the outer side thereof, projects a spindle, F, and above the spindle, at the inner end thereof, is formed a segmental flange, G.

30 As a matter of choice, I prefer to form the standard, flange, and spindle of a single piece of metal; but they may be otherwise constructed, if preferred. This standard is secured to one side of the drill-hoe, near the lower end 35 thereof, by means of a bolt, H, which extends through the slot D, and a bolt, I, that extends through the opening E. Nuts H' and I' are on the ends of the said bolts H and I, respectively. The nut H' bears on the outer side of the 40 standard at its outer end, but on the bolt I, between the outer side of the standard and the opposing face of the nut I', is placed a bridge-bar, K, which spans the opening E, and has a slot, K', in which the shank of the bolt I 45 works. By means of the slot D and the opening E it will be readily understood that the standard may be adjusted vertically with relation to the drill-hoe, and its lower end moved forwardly or rearwardly thereon. By 50 clamping the nuts H' and I' the standard may be secured to the drill-hoe at any desired adjustment, as will be very readily understood.

L represents a wheel, of small diameter and comparatively broad tread, which is journaled on the spindle F, and is provided with 55 central peripheral walking studs or projections, L'. A washer, M, which is provided on its inner side with a segmental flange, M', is placed on the outer end of the spindle, and the flange M' bears on the upper side of the 60 outer end of the hub of the wheel. Ears M² project from the front side of the washer M, and in the space between these ears is inserted a linchpin, N, which passes down through an opening made in the outer end of the spindle, 65 and thereby secures the wheel thereon.

The object of my invention is to provide means to enable the drill-hoe to force its way through trash—such as pea-vines or other rubbish—which may lie on the surface of the 70 ground to be drilled; and the object of my invention is, further, to provide a means for regulating the depth at which the seed shall be planted.

The operation of my invention is as follows: 75 As the drill is drawn along the wheel L, by reason of its studs L', comes in contact with the earth and is rotated thereby, and the weight of the drill-hoe is borne by the said wheel. When trash is encountered, the rotation of the wheel causes it to be swept rearwardly past the drill-hoe and broken, and thus prevents the trash from impeding the motion of the drill-hoe by choking it up. As the weight of the drill-hoe is borne by the 85 wheel, and as the latter, by reason of the slotted standard, may be adjusted vertically or back and forth with relation to the drill-hoe, it follows that the depth at which the latter shall run in the ground may be very readily 90 regulated, and thus cause the seeds to be planted in the ground at any desired depth.

Having thus described my invention, I claim—

1. The combination, with the drill-hoe, of 95 the standard having the slot D, the opening E, and the spindle projecting at right angles from one side of the standard, the bolt H, extending from one side of the drill-hoe and working in the slot D, the bolt I, extending from 100 one side of the drill-hoe and working in the opening E, whereby the standard is secured to one side of the drill-hoe, and may be adjusted vertically and laterally thereon, and the

supporting-wheel journaled on the spindle and running alongside the hoe, substantially as described.

2. The combination, with the drill-hoe, of the standard secured on one side thereof, and adjustable vertically and laterally thereon, and the supporting-wheel journaled on a spindle projecting from the lower end of the standard, substantially as described.

10 3. The combination of the drill-hoe, the standard having the slot D, the opening E, and the spindle F, the slotted bridge-bar spanning the opening E, the bolt I, passed through

the said bar and opening E and entering the side of the drill-hoe, and the bolt H, projecting from the side of the drill-hoe and working in the slot D, and the supporting-wheel journaled on the spindle F, substantially as described.

In testimony that I claim the foregoing as my own I have hereto affixed my signature in presence of two witnesses.

ALLIE DILLARD.
